UNITED STATES PATENT OFFICE.

CALVIN D. McALLUM, OF DE KALB, MISSISSIPPI.

SYRINGE.

1,115,224.

Specification of Letters Patent. Patented Oct. 27, 1914.

Application filed March 30, 1914. Serial No. 828,314.

To all whom it may concern:

Be it known that I, CALVIN D. McALLUM, a citizen of the United States, residing at De Kalb, in the county of Kemper and State 5 of Mississippi, have invented new and useful Improvements in Syringes, of which the following is a specification.

My present invention relates to instruments for the treatment of the female organ 10 of generation, and has for its object to provide efficient means for irrigating or medicating the uterus and adjacent parts.

Another object of the invention is the provision of means whereby the said treatment 15 will cause but slight pain, and tend to make the treatment less disagreeable than is the case with devices of this kind at present in use.

Still another object is the provision of 20 means whereby the womb or parts of the vagina may be held in place while a doctor or attendant is treating an ulcer or cancer thereof, and at child-birth the device is indispensable to cleanse the womb and to withdraw 25 the placenta.

Other advantageous features of my invention will be fully understood from the following description and claims when the same are read in connection with the drawings, accompanying and forming part of 30 this specification, in which:

Figure 1 is a side elevation of my novel device as applied to a syringe, and showing the rubber tubes I employ as surrounding 35 and attached to the steel or gutta-percha nozzle of a syringe; two of the tubes being broken away. Fig. 2 is a view of my novel device, showing the cap or head of the nozzle in section, and surrounded by the tubes, 40 and also showing in section the ring to which the tubes are connected at their lower ends; the lower portion of the nozzle being omitted for convenience of illustration. Fig. 3 is a detail view of the ring, showing 45 the air inlet in proper position.

Similar numerals of reference designate corresponding parts in all of the views of the drawings.

My novel device comprises among other 50 features a ring 1, having apertures 2 in its

upper face, the said apertures receiving short tubes 16, and at 3 I provide in the ring a neck, which neck is in communication with tubing 4, the said tubing being of the ordinary well known construction, and in turn 55 is connected at its end remote from the neck, to a bulb 5.

Mounted upon and fixedly connected to and in communication with the apertures 2 through the medium of the short tubes 16 60 are tubes 6 of rubber or other inflatable material, and at 7 the said tubes are fixedly attached to a nozzle of a syringe. At this point I would have it understood that my device is capable of attachment to any kind 65 of syringe now in use, but for the sake of illustrating the practicability of my novel device, I have shown a syringe comprising a bulb 9 snugly retaining in its neck a nozzle 10 formed of gutta-percha or other suitable 70 material, the said neck inclosing the nozzle. The nozzle 10 is provided in its face with openings 11 and a cap or head 12; the said cap being also provided with an opening 13.

As will be readily appreciated by reference to the drawings, the tubes 6 are increased in diameter at a point slightly beyond their centers, as indicated by 14, for a very important purpose hereinafter pointed out.

In applying my novel device to a syringe, 75 it is simply necessary to place the ring 1 over the head 12 of the nozzle 10, and run the ring down so that it will seat around the neck of the bulb 9, and then attach the 80 tubes 6 at their upper ends through the medium of adhesive to the sides of the head 12 of the nozzle, and when this has been done, it will be seen that the said tubes 6 extend slightly beyond the cap or head 12 85 of the syringe, for a reason which will also be pointed out later.

In the practical operation of my device, 90 where it is desired to cleanse the womb and parts thereof, the bulb 9 of the syringe, 95 equipped with my improvements, is filled with water or other cleansing agent, then the nozzle 10 is inserted into the vagina, and as the tubes surrounding the cylinder are not inflated until after insertion of the de- 100

vice, it will follow that the device is not materially increased in diameter, and this together with the further fact that the soft rubber tubes 6 extend a short distance beyond the head 12 of the nozzle, and thereby serve as a cushion for the said head, the insertion of the device will not be attended with pain. After the device has been inserted, it is only necessary to inflate the tubes 6 through the medium of the air bulb 5, thereby holding the parts open, which will allow water or other fluids to pass freely through the several passages into the vagina, when the fluid is forced, by pressing of the bulb 9, to pass through the gutta-percha tube 10 and out of the openings 11 and 13 in said tube.

The apparatus is indispensable in the treatment of ulcers or cancer of the womb, as in such cases after the device is inserted it is only necessary to inflate certain of the tubes, leaving the ones covering the infected part uninflated, stopping all the openings 11 in the nozzle, except those wished to be used, and thereby giving the doctor or attendant free use of his hands.

It will be gathered from the foregoing that my invention is inexpensive to produce, simple to operate and capable of easy and ready attachment to any style of syringe.

The construction shown and described is the preferred embodiment of my invention, but I would have it understood that in the future practice of my invention such changes or modifications may be made as fairly fall within the scope of the same as claimed. In the small sizes, four tubes only will be used.

Having described my invention, what I claim and desire to secure by Letters-Patent, is:

1. The combination with a syringe, of a hollow ring having tubes in communication therewith, a hollow neck contained in said ring and inflatable tubes connected at the upper portions of the first-named tubes.

2. The combination with a syringe, of a hollow ring having tubes in communication therewith through the medium of apertures in the face of the ring, a hollow neck arranged at one side and in communication with the ring, and inflatable tubes connected to the first-named tubes at the upper ends thereof, whereby when air is introduced into the neck of the ring the tubes will be inflated.

3. The combination with a syringe, of a hollow apertured ring having tubes seated in the said apertures and in communication with the ring, a hollow neck arranged in one side wall of the ring, and inflatable tubes of increased diameter at their upper portions; the said inflatable tubes being connected to the first-named tubes.

4. The combination with a syringe, of a

hollow apertured ring receiving tubes in its said apertured portions, a hollow neck arranged in one side of the ring in communication through a hose with an air bulb, inflatable tubes the upper portions of which are of increased diameter; the said tubes being in communication at their lower ends with the ring whereby air may be supplied to the inflatable tubes, and the upper portion of the said tubes being fixedly connected to and surrounding the nozzle of a syringe.

5. The combination in a syringe, of a nozzle provided with a cap at its upper end, and having outlets in its face below the cap; the said cap being provided with an outlet, a bulb having a hollow neck capable of receiving and holding the lower portion of the nozzle in fixed relation to the bulb, a hollow ring provided with openings in its face receiving the lower ends of tubes, inflatable tubes in communication with the upper portions of the first-named tubes and the upper portions of the inflatable tubes surrounding and fixedly connected to the cap of the nozzle.

6. The combination in a syringe, of a nozzle provided with a cap at its upper end and having outlets in its face below the cap; the said cap being provided with an outlet, a bulb having a hollow neck capable of receiving and holding the lower portion of a nozzle whereby fluid may be forced through the nozzle, a hollow ring provided with openings in its face for receiving the lower ends of tubes and also having a hollow neck in communication with an air bulb, inflatable tubes mounted on the upper portions of the first-named tubes whereby air may be introduced into the inflatable tubes through the medium of the air bulb; the upper portions of the inflatable tubes being of a greater diameter than their lower portions, and means for connecting the inflatable tubes with the sides of the cap.

7. As a new article of manufacture, a syringe provided with cushioning means comprising a hollow ring having a hollow neck in communication with an air bulb, apertures in the face of the ring, tubes retained in the said apertures and inflatable tubes receiving at their lower ends the upper portion of the first-named tubes and being at their upper ends fixedly held in spaced relation to the nozzle of a syringe.

8. A syringe comprising a central rigid and apertured nozzle, inflatable tubes grouped about and connected with the rigid nozzle, and means for inflating said tubes.

9. A syringe comprising a central rigid and apertured nozzle, and inflatable tubes grouped about and connected with the nozzle; the tubes being extended beyond the forward end of the nozzle, and means for inflating the tubes.

10. A syringe comprising a rigid apertured nozzle; tubes grouped about the nozzle and having forward inflatable portions connected with the nozzle, and means connected with the tubes for distending the forward portions thereof.

In testimony whereof I have hereunto set

my hand in presence of two subscribing witnesses.

CALVIN D. McALLUM.
